SYMBOLIC FLAGPOLE STAND

Cecil E. Click, Box 67, Pala, Calif. 92059

Filed Jan. 24, 1968, Ser. No. 10,290

Term of patent 14 years

(Cl. D29—17)

Fig. 1

Fig. 2

Fig. 3

I claim:

The ornamental design for a symbolic flagpole stand, as shown.
